UNITED STATES PATENT OFFICE.

JOHN H. REDSTONE AND ALBERT E. REDSTONE, OF INDIANAPOLIS,
INDIANA.

IMPROVEMENT IN VALVES FOR STEAM-ENGINES.

Specification forming part of Letters Patent No. 35,174, dated May 6, 1862.

To all whom it may concern:

Be it known that we, JOHN H. REDSTONE and ALBERT E. REDSTONE, of Indianapolis, in the county of Marion and State of Indiana, have invented certain new and useful Improvements in the Construction and Arrangement of Steam-Engines; and we do hereby declare that the following is a full and exact description of the same, reference being had to the accompanying drawings and the letters marked thereon.

Figure 1 is a section showing the steam-chest and cylinder longitudinally through the center. Fig. 2 is a top view of the valve of a single engine, designed to explain the position of the ports or steam-channels shown in Fig. 1.

A is a hollow rolling valve. The letters D, E, C, and F show the ports and steam-space connected with the same.

B is the lever which operates the valve A, being operated by the connection-rod R.

The branch passages H and I K and L communicate with the cylinder-ports J and M. The steam-pipe N communicates with the steam-space C, as indicated by the dotted lines leading to the same.

G represents the escape-pipe attached to the hollow valve A.

The operation of the engine is as follows: The steam being admitted through the supply-pipe N enters the steam-space C. The port E, being in communication with the branch passage L, conducts the steam to the cylinder-port M, and, acting upon the inner side of the piston-head O, forces the same out, revolving the fly-wheel P, the exhaust escaping through the cylinder-port J, passage H, and escape-pipe G, which are now in connection, as indicated by the dotted lines, showing the valves E and F. The valve A being operated as the lever R is withdrawn by the action of the fly-wheel P', the valve making one-fourth of a revolution, brings the port P (shown in Fig. 2) in communication with the branch passage K and the supply-port D in communication with the passage L, thus opening the supply of the steam through the passage

I and cylinder-port J to the outer side of the piston-head O, thereby perfecting the revolution of the fly-wheel P'. Fig. 3 shows the throttle of the double engine, and is also used to reverse the motion of the same, as will be shown. The steam entering the supply-pipe A to the steam-space B, surrounding the valve C, the connection is now shown as open through the valve C at the connection of the passages D and E, which will be shown to communicate with the rolling valves F and G (shown in Fig. 4) as follows: the valve C resting upon the valve-seat H, and the passages D and E connecting with the steam-space surrounding the rolling valves F and G, while the passages J and K connect with the passage L and M, which lead to the rolling valves F and G. In the position in which the valve F is shown in Fig. 4, with the position of the valve C as in Fig. 3, the steam is admitted, as indicated by the dotted lines in the valve C, to the passages L and M. The steam passes through the valve F to the cylinder-port N, while the exhaust passes through the port O to the steam-space surrounding the valve, as shown by the dotted lines, thence up the passage D (shown in Fig. 3) to the exhaust of the throttle C. The valve G is operated at a difference of one-fourth of a revolution by the same process.

Fig. 5 is an under view of the cap of the steam-chest shown in the section, Fig. 3, and shows the throttle-chamber, valve-cavities, and steam-channels leading to the same. Figs. 6 and 7 are end sections, showing the valve ports and passages leading to the steam-space.

What we claim, and desire to secure by Letters Patent, is—

1. The hollow valve A, when constructed as set forth and operated in connection with the steam-passages H I and K L.
2. The valves F and G, when constructed and operated as set forth.

JOHN H. REDSTONE. [L. S.]
ALBERT E. REDSTONE. [L. S.]
